Primary Examiner — Michelle E. Wilson*Assistant Examiner* — Clese Moore, Jr.(74) *Attorney, Agent, or Firm* — Levenfeld Pearlstein, LLC(57) **CLAIM**

The ornamental design for stem mounted mirror, as shown and described.

DESCRIPTION

FIG. 1 is a front perspective view of a stem mounted mirror embodying my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dashed lines in FIG. 7 are for environment only and form no part of the claimed design.
